UNITED STATES PATENT OFFICE.

EDWARD A. MALMGREN, OF DULUTH, MINNESOTA.

CAR-TILTING MECHANISM.

Application filed October 16, 1925. Serial No. 62,799.

This invention relates to a new and improved car tilting mechanism and more particularly, to an apparatus for tilting cars in such manner as to dump from them the material which they contain.

In dumping small cars of this type heretofore, the dumping has been usually accomplished by running the cars up against a stop with sufficient velocity so that the momentum of the car and car contents will cause the car to tip upon meeting the stop. This method of dumping is very hard on the cars and does not afford a positive and uniform dumping action.

It is an object of the present invention to provide mechanism adapted to positively engage a car and tilt it to a dumping position.

It is a further object to provide a structure of this character in which means are provided for automatically locking the car to the mechanism during the tilting movement.

It is also an object to provide construction in which the car engaging elements have a cushioned connection to the remainder of the tilting mechanism whereby the shock of the engagement of the car is taken up.

Other and further objects will appear as the description proceeds.

I have illustrated a preferred embodiment of my invention in the accompanying drawings, in which—

Figure 1 is a sectional elevation of the apparatus;

Figure 2 is a view of Figure 1 as seen from the right;

Figure 3 is a view similar to Figure 2, but showing the car in the tilted position;

Figure 4 is a plan view of the mechanism, and

Figure 5 is a fragmentary side elevation of the car engaging mechanism.

In the drawings, the dump car 11 is supported from rails 12 by the trucks 13 and wheels 14. The dumping bar 15 is secured to the car truck by the brackets 16. The concrete lined pit 17 is located between the rails 12. This pit contains the cylinder 18 which is provided with pipes 19 and 20 adapted for the admission of fluid under pressure at the opposite ends of the cylinder. The piston 21 and piston rod 22 work in the cylinder 18. The head 23 is rigidly secured to the top of the piston rod 22 by means of the pin 24.

As best shown in Figure 4, this head 23 is provided with the laterally extending lugs

25 through which slide the rods 26. The hook 27 is supported at its rear end upon the transverse shaft 28 which shaft is supported at its ends in the members 29. The members 29 have their lower portions 30 fitting upon and secured to the rods 26. The lower portion of the hook 27 is split and the lock member 31 is supported upon the rod 29 between the divided portions of the hook 27.

The cross bar 32 is fitted upon the forward ends of the rods 26 and is provided with perforated lugs 33 between which fits the similar lug 34 formed on the hook member 27. These lugs are held in fixed relation by the pin 35. It is to be understood that the cross bar 32 and the members 30 are positively secured to the rods 26. The portions 25 of the head are slidably fitted upon the rods. The springs 36 are fitted upon the rods 26 between the members 25 and 30.

As best shown in Figures 1 and 3, the top of the piston rod 22 is provided with an axially extending bore in which are fitted a plunger 37 and spring 38. The plunger engages the front portion of the lock member 31. When the parts are in the lower position as shown in Figure 1, the tail 39 of the lock member 31 engages the fixed stud 40.

In the operation of the device with the parts in the position shown in Figure 1, the car is run forward until the bar 15 engages the hook 27. The car is stopped without shock to the apparatus since the hook is free to move forward relative to the piston rod and head. As it moves forward the rods 26 pass through the lugs 25 on the head and the springs 36 are compressed. Fluid under pressure is now admitted through pipe 19 into the bottom of the cylinder and the piston head 21 and piston 22 are forced upwardly to the position of Figure 3. As soon as the tail 39 of the lock member 31 clears the stud 40, the plunger 37 under the influence of the spring 38 forces the locking member upwardly to close the mouth of the hook 27. This effectively retains the car connected to the mechanism during the tilting operation.

Fluid under pressure is next applied through pipe 20 to the top of the cylinder 18 and the fluid under pressure below the piston is released. The piston and piston rod are lowered and during their movement restore the car to normal position. As the

tail of the lock member 31 engages the stud 40 the forward end of the member is lowered and the hook member is thus opened and the emptied car may then be drawn away 5 from the hook and the apparatus is ready to repeat the cycle with another car. If it is desired to pass cars over the dumping mechanism, the key 35 may be withdrawn and the hook 27 thrown over to the dotted 10 line position of Figure 1. When in this position, cars will pass over the hook without engaging it.

I have shown one preferred form of construction by way of illustration, but it is 15 to be understood that I contemplate such changes and modifications as come within the spirit and scope of the appended claims.

I claim:

- 20 1. Car tilting mechanism comprising a stop member adapted to engage a portion of the car to arrest movement of the car, means adapted to lock the car to the stop means, and means adapted to elevate the stop member to tilt the car.
- 25 2. Car tilting mechanism comprising a stop member adapted to engage a portion of the car to arrest movement of the car, means adapted to elevate the stop member to tilt the car, and a member adapted to lock the car to the stop member as the stop member is elevated and to release the car 30 as the stop member is lowered.

3. Car tilting mechanism comprising a stop member adapted to engage a portion of the car to arrest movement of the car, 35 cushioning means for the stop member, and elevating mechanism adapted to raise and lower the stop member and cushioning means.

4. Car tilting mechanism comprising a 40 stop member adapted to engage a portion of the car to arrest movement of the car, cushioning means and locking means for the stop member, and elevating mechanism adapted to raise and lower the stop member, 45 locking means and cushioning means.

5. Car tilting mechanism comprising stop means normally in the path of a portion of a car, means for elevating said stop means, and connecting means for the stop and elevating means whereby the stop means may be moved out of the path of the car. 50

6. Car tilting mechanism comprising a hook adapted to engage over a portion of the car, locking means adapted to close the mouth of the hook to lock the car to the hook, means adapted to elevate the hook to tilt the car, and a member adapted to engage the locking means when the hook is 55 in its lower position to move it clear of the mouth of the hook. 60

Signed at Duluth, Minnesota, this 12th day of October, 1925.

EDWARD A. MALMGREN.
